(57) **CLAIM**

The ornamental design for a chocolate bar, as shown and described.

DESCRIPTION

FIG. 1 is a perspective view of the chocolate bar showing our new design, according to a first embodiment;

FIG. 2 is a top view of the design shown in FIG. 1;

FIG. 3 is a bottom view of the design shown in FIG. 1;

FIG. 4 is a left view of the design shown in FIG. 1;

FIG. 5 is a right view of the design shown in FIG. 1;

FIG. 6 is a front view of the design shown in FIG. 1;

FIG. 7 is a rear view of the design shown in FIG. 1;

FIG. 8 is a perspective view of a chocolate bar showing our new design, according to a second embodiment;

FIG. 9 is a top view of the design shown in FIG. 8, the bottom view being identical to that shown in FIG. 3;

FIG. 10 is a left view of the design shown in FIG. 8;

FIG. 11 is a right view of the design shown in FIG. 8;

FIG. 12 is a front view of the design shown in FIG. 8; and,

FIG. 13 is a rear view of the design shown in FIG. 8.
